UNITED STATES PATENT OFFICE.

CHARLES MAUNDEES, OF MINOT, NORTH DAKOTA.

TRACK-BRACE.

974,411.

Specification of Letters Patent. Patented Nov. 1, 1910.

Application filed April 28, 1910. Serial No. 557,252.

To all whom it may concern:

Be it known that I, CHARLES MAUNDERS, citizen of the United States, residing at Minot, in the county of Ward and State of North Dakota, have invented certain new and useful Improvements in Track-Braces, of which the following is a specification.

The present invention comprehends certain new and useful improvements in track equipment for railways, and the invention has for its object an improved track brace which extends transversely between the rails and is securely engaged therewith, whereby to prevent the rails from spreading apart and to maintain the proper gage of the track.

Another object of the invention is a track brace which is designed particularly for use in connecting the meeting ends of the rails, and which provides very efficient joints.

A further object of the invention is a device of this character which may be readily applied to the rails, and which does not require subsequent attention, a material economy being thus effected in the cost of construction and maintenance of the track.

With these and other objects in view as will more fully appear as the description proceeds, the invention consists in certain constructions, combination and arrangements of the parts, that I shall hereinafter fully describe and claim.

For a full understanding of the invention and the merits thereof, and to acquire a knowledge of the details of construction, reference is to be had to the following description and accompanying drawings, in which:

Figure 1 is a sectional perspective view illustrating the application of my improved track brace; Fig. 2 is a horizontal section; Fig. 3 is a section on the line 3—3 of Fig. 2; and Fig. 4 is a detail perspective view of one of the U-shaped clips detached.

Corresponding and like parts are referred to in the following description and indicated in all the views of the drawings by the same reference characters.

For the purpose of illustration the present invention is shown and described in connection with a railway track consisting of a pair of rails 1 and the usual wooden cross ties 2.

The improved track brace forming the subject matter of the invention, includes an elongated base plate or tie plate 3 that is

laid upon the upper face of one of the cross ties 2 and extends transversely beneath the rails. The base plate is constructed of any suitable metal and may be of any suitable thickness and width in order to possess the necessary rigidity and durability. The end portions of the base plate project upwardly and constitute wings 4 which conform to the contour of and lie snugly against the outer sides of the rails 1. Although the track brace may be advantageously employed at points intermediate of the ends of the rails, it is preferably placed at the joints, as shown in the drawings, so that the wings 4 span said joints. In this instance the meeting ends of the rails are well supported upon the base plate and thus low joints are avoided. Each wing is formed in its outer face with reinforcing rib 5 that is located opposite the joint to strengthen the structure at this point. At its upper end the wing lies against the web portions of the adjacent rail ends and is preferably extended longitudinally in the direction of the rails, as shown, so as to have a broader bearing thereagainst.

An elongated plate 6 is superimposed upon the base plate 3 between the rails and has its end portions upturned to constitute wings 7. The plate 6 is somewhat shorter than the base plate, by virtue of which arrangement the wings 7 are supported in spaced relation to the wings 4 and lie snugly against the inner sides of the rails. The opposed wings at the adjacent ends of the plates coöperate to form, in effect, chairs in which the respective rails are seated, the rails being thus effectually held in proper spaced relation to maintain the desired gage of the track. The wings 7 have a similar contour to the wings 4 and are extended longitudinally at their upper ends and are provided with reinforcing ribs 8 opposite the joints.

Intermediate of its ends and preferably in proximity to its middle point, the plate 6 is rigidly secured to the base plate 3 in any suitable manner, as for instance, by being welded. A spike 10 is inserted through registering apertures in the middle portions of the plates and is driven into the cross tie 2. The function of the spike is to secure the track base in position on the tie and also to further secure the plates 3 and 6 together.

The pairs of wings at each end of the track brace are formed with longitudinal series of openings 11 which register with

openings in the web portions of the meeting ends of the rails. Bolts 12 are passed through the intermediate openings of the series to secure the wings and rail ends together, the nuts 13 of said bolts being all positioned in abutting relation to the wing 4. As a further means for connecting the meeting ends of the rails, I employ a U shaped clip that includes a splice bar 14 which lies longitudinally against the outer face of the wing 4 and is suitably curved or bent intermediate of its ends, as indicated at 15, to embrace the rib 5. The bar is formed with a plurality of sockets 16 into which the respective nuts 13 are fitted so as to be held against turning movement on the bolts, the sockets being preferably elongated, as shown, so as to compensate for expansion and contraction of the parts. At the opposite ends of the bar are substantially perpendicularly disposed threaded stems 17 that pass through the extreme openings 11 of the series and are engaged by nuts 18 that are tightened up against the wing 7. The extremities of the threaded stems are split, as indicated at 19, and are formed with interiorly threaded sockets 20. The nuts 18 are screwed up past the split extremities, and threaded plugs 21 are then inserted in the sockets 20, the plugs having a slightly tapered contour, whereby to expand the split extremities of the stems and thus effectually prevent the nuts 18 from becoming accidentally detached. At their outer ends the plugs are provided with relatively small angular heads 22 to which a wrench may be fitted to turn the plugs. If desired the heads may be also formed with suitable openings to admit of the plugs being manipulated by a screw driver. To retain each plug against loosening movement I provide a pin 23 that is inserted through transverse apertures in the plug and the stem. The ends of the pins are upset and may be substantially hidden from view, if desired, by upsetting the threads of the stems thereover.

From the foregoing description in connection with the accompanying drawings, it will be apparent that I have provided an improved track brace which materially reinforces the track and also serves to positively hold the rails in proper spaced relation and to prevent the same from tilting laterally. The brace is thoroughly practical and possesses to a marked degree durability and strength. When applied at the rail joints the brace establishes a very rigid union between the rail ends. Attention is particularly directed to the fact that all of the nuts are locked against loosening movement, and hence the necessity of employing track walkers to keep the nuts tightened up, is avoided.

65 It is to be understood that the co-acting

wings or fish-plates which lie against opposite sides of the rails, may be so formed as to engage either the webs or base flanges of the rails, or both.

Having thus described the invention, what is claimed as new is:—

1. In a rail joint having bolts for securing together the meeting ends of the rails, means for locking all of the nuts on the bolts, said means spanning the joint and being fixed to the rail ends to assist in tying the same together.

2. In a rail joint having bolts for securing together the meeting ends of the rails, means for locking the nuts on the bolts, said locking means spanning the joint and being provided with angularly disposed stems secured through the respective rail ends.

3. In a rail joint having bolts for securing together the meeting ends of the rails, a bar lying against one side of the rails and formed with sockets in which the nuts on the bolts are received and locked, and means for fixing the bar to the respective rail ends, whereby to assist in tying the rail ends together.

4. The combination with a track brace having a pair of co-acting wings to fit against opposite sides of an interposed rail, a splice bar lying against the outer face of one of the wings and formed with a plurality of sockets, the splice bar having stems secured through both of the wings and the interposed rail, a plurality of bolts passing through the wings and the rail, and a plurality of nuts working on the bolts and received in the sockets and held therein against turning movement.

5. The combination with a track brace including a pair of co-acting wings fitted against opposite sides of an interposed rail, one of said wings being formed in its outer face with a reinforcing rib, a splice bar lying against the outer face of the last named wing and bowed intermediate of its ends to embrace the rib, the splice bar having a plurality of sockets and also having stems secured through both of the wings and the interposed rail, a plurality of bolts passing through the wings and rail, and nuts working on the bolts and received in the respective sockets in the splice bar and held therein against turning movement.

6. In a rail joint, the combination with the meeting ends of the rails, members fitting against opposite sides of the rails and spanning the joint, a splice bar lying against the outer face of one of the members and having angularly disposed stems secured through both of the members and through the respective rail ends, the splice bar being formed with a plurality of sockets, bolts passing through the members and the rail ends, and the nuts working on the bolts and received in the respective sockets in the

splice bar and held therein against turning movement.

7. In a rail joint, the combination with the meeting ends of the rails, of members fitting against opposite sides of the rails and spanning the joint, bolts passing through the members and the interposed rail ends, nuts working on the bolts in abutting relation to one of the members, a splice bar lying against the outer face of the last named member and formed with a plurality of sockets receiving the nuts to hold the same against turning movement, the splice bar

having angularly disposed stems passing transversely through the members and the rail ends, nuts working threaded on the extremities of the stems, and locking means for holding the last-named nuts against loosening movement.

In testimony whereof, I affix my signature in presence of two witnesses.

CHARLES MAUNDERS. [L.S.]
